(57) **CLAIM**

The ornamental design for a flexible glove with a pebble pattern and a flared cuff, as shown and described.

DESCRIPTION

FIG. 1 is a front elevation view of the flexible glove with a pebble pattern and a flared cuff in accordance with our design, wherein the glove is illustrated for a left hand; and wherein a front elevation view of a glove for a right hand is a mirror image thereof;

FIG. 2 is a rear elevation view of the glove of FIG. 1, wherein a rear elevation view of the glove for the right hand is a mirror image thereof;

FIG. 3 is a left side elevation view of the glove of FIG. 1, wherein a left side elevation view of the glove for the right hand is a mirror image thereof;

FIG. 4 is a right side elevation view of the glove of FIG. 1, wherein a right side elevation view of the glove for the right hand is a mirror image thereof;

FIG. 5 is a top plan view of the glove of FIG. 1, wherein a top plan view of the glove for the right hand is a mirror image thereof;

FIG. 6 is an enlarged detail view of the area circumscribed within FIG. 1, showing the pebble pattern that is provided on the gripping surfaces of the glove; and,

FIG. 7 is an enlarged cross-section of the pattern shown in FIG. 6.

The broken lines in the drawings show portions of the glove or environment and form no part of the claimed design. The dot-dot-dash line surrounding the detail area in FIG. 1 and corresponding view in FIG. 6 depicts the boundary of the detail and forms no part of the claimed design.
